UNITED STATES PATENT OFFICE.

ROBERT H. KOENIG, OF CAMDEN, NEW JERSEY, ASSIGNOR, BY DIRECT AND MESNE ASSIGNMENTS, TO NICHOLAS A. PETRY, OF PHILADELPHIA, PENNSYLVANIA.

MAKE-AND-BREAK IGNITER FOR EXPLOSIVE-ENGINES.

No. 881,009.

Specification of Letters Patent. Patented March 3, 1908.

Application filed January 29, 1907. Serial No. 354,722.

To all whom it may concern:

Be it known that I, ROBERT H. KOENIG, a citizen of the United States, residing in Camden, New Jersey, have invented certain improvements in Make-and-Break Igniters for Explosive-Engines, of which the following is a specification.

The object of my invention is to so construct a "make-and-break" electric igniter for explosive engines that the circuit through the electrodes will be maintained only during the limited period necessary for the production of the spark, the opening and closing of the circuit being effected automatically by variations of pressure in the cylinder of the engine.

In the accompanying drawing:—Figure 1 is a sectional view of a make-and-break igniter constructed in accordance with my invention, the parts being in the position assumed by them when the circuit is open; Fig. 2 is a similar view showing the parts in the position assumed just after the circuit has been closed and before the separation of the electrodes for producing the spark; Fig. 3 is a similar view but illustrating the electrodes separated to produce the spark; Fig. 4 is a perspective view of one of the electrodes and its carrier; Fig. 5 is a perspective view of the other electrode and its carrier; Fig. 6 is a transverse section of the latter structure; and Figs. 7, 8 and 9 are views representing, in different positions, a special form of circuit opener and closer which I sometimes employ.

In the drawing, 1 represents part of the head of the cylinder of a gas engine, a gasoline engine, or other engine of the explosive or internal combustion type, and 2 represents a tubular plug screwed into a threaded opening in said head and having in its outer end a screw cap 3.

Guided within the plug 2 is a tubular plunger 4 having a hollow stem with shoulder 5 and enlarged hollow head 6, the lower end of the latter being closed by a plug 7 insulated from the plunger and also having an insulated connection with a rod 9, the latter being likewise insulated from the stem of the plunger and being provided, at its outer end, with means for connecting to it one of the battery wires 10, the other pole of the battery being in connection with the head 1 of the cylinder.

55 Into the lower open end of the plug 2 is

screwed a ring 11, having a transverse bridge bar 12, with central boss carrying an adjusting screw 13, which constitutes one of the electrodes of the igniter and is preferably provided with a platinum tip 14.

60 The plug 7 is hollow and contains a chamber 15 across the bottom of which extends a bridge bar 16 having a depending stem 17 which constitutes the other electrode of the igniter and is also, by preference, provided with a platinum tip 19.

By adjustment of the electrode 13, the extent of separation of the electrodes to produce the spark can be readily regulated.

65 The chamber 15 of the plug 7 contains a block 20 of less vertical dimensions than said chamber and free to rise and fall therein, the top of the block being inclined or beveled as shown.

70 Between the shoulder 5 on the stem of the plunger 4 and the inner end of the screw cap 3 is interposed a coiled spring 21, the tension of which can be readily regulated by adjustment of the said screw cap 3, downward movement of the plunger being prevented by contact of the tips of the electrodes.

75 Normally, the parts occupy the relations shown in Fig. 1 the electrodes being in contact but out of circuit, owing to the fact that the conducting rod 9 is insulated from the plug 7 which carries the upper electrode. Under these circumstances the block 20 rests upon the bridge bar 16 of said upper electrode and is free from any contact with the lower end of the conductor rod 9.

80 On the compression stroke of the engine, however, the block 20 is forced upwardly in the chamber 15 by the pressure to which it is subjected and its beveled upper face is brought into contact with the lower end of the rod 9, the block being thereby tipped or tilted so as to bring it into forcible contact with the walls of the chamber 15, as shown in Fig. 2, thus completing the electrical connection between the rod 9 and the upper electrode through the plug 7 and the bridge bar 16.

85 When the compression reaches its maximum the pressure on the lower end of the plunger overcomes the downward pressure 105 of the spring 21 thereon and said plunger is accordingly lifted so as to separate the electrodes and produce the spark as shown in Fig. 3. As soon as the pressure in the cylinder, due to the expansion of the exploded 110

gases therein, is reduced below the point of resistance of the spring 21 the latter again forces the plunger downwardly and brings the electrodes into contact, and as the pressure is still further reduced the block 20 falls in the chamber 15 and opens the circuit which remains open until the next compression stroke, whereupon the operations described are repeated.

- 10 In that form of circuit closer and opener shown in Figs. 7, 8 and 9, the plug 20 fits snugly in the chamber 15 of the plunger and has a flat top and depending legs 25, one on each side of the bridge bar 16, each leg having a hooked lower end 26, which underlaps the ring 11. Normally the plug rests on the bar 16 and is free from contact with the rod 9, as shown in Fig. 7, but is raised by the pressure in the cylinder so as to contact with the rod and close the circuit, as shown in Fig. 8. When the plunger 4 is raised, the first effect of the movement is to separate the electrodes and produce the spark, and as the movement continues the hooked lower ends of the legs 25 of the block 20 come into contact with the ring 11, and arrest the further upward movement of the block with the plunger, whereupon the block is removed from contact with the rod 9 and the circuit is opened. This device is in many cases preferable to that shown in Figs. 1, 2 and 3, because there is less liability to interference with its action by carbon accumulating in the chamber 15 of the plunger.
- 35 By reason of the fact that with either form of device which I have shown and described, the battery which supplies the current is in circuit only during the formation of the spark and for a very limited period before and after that time, rapid exhaustion of the battery which results when the same is continuously in circuit is prevented, while, owing to the fact that both the opening and closing of the circuit and the separation of the electrodes are due to variations of pressure in the cylinder the device is rendered entirely automatic in its action and expensive and troublesome mechanical devices for the purpose are rendered unnecessary.
- 50 A pressure-actuated circuit opener and closer in accordance with my invention may, however, if desired, be employed in connection with mechanical devices for effecting separation of the electrodes to produce a spark, although the construction shown, in which the pressure within the cylinder performs both of these operations, is preferred.

I claim:—

- 60 1. The combination of the electrodes of a make-and-break igniter for explosive engines with a circuit-opener-and-closer actuated by variations of pressure in the cylinder and serving to control the circuit independently of the movement of the electrodes.
- 65 2. The combination of the electrodes of a

make-and-break igniter for explosive engines operated by pressure in the cylinder to separate the electrodes and produce the spark, and a circuit-opener-and-closer likewise operated by variations of pressure in the cylinder. 70

3. The combination of the electrodes of a make-and-break igniter for explosive engines operated by pressure in the cylinder to separate the electrodes and produce the spark, and a circuit-opener-and-closer likewise operated by variations of pressure in the cylinder and constructed to close the circuit through the electrodes before the pressure in the cylinder acts to separate the same. 75 80

4. The combination of the cylinder of an explosive engine carrying one of the electrodes of a make-and-break igniter, a sliding plunger carrying the other electrode and acted upon in one direction by a spring and in the other direction by the pressure in the cylinder, and a pressure-actuated circuit-opener-and-closer likewise carried by said plunger. 85

5. The combination of the cylinder of an explosive engine carrying one of the electrodes of a make-and-break igniter, a sliding plunger carrying the other electrode, a conductor rod insulated from the plunger and a block movable in a chamber of the plunger and serving by variations of pressure upon it to make and break connection between the conductor rod and the plunger. 90 95

6. The combination of the cylinder carrying one of the electrodes of a make-and-break igniter, a sliding plunger carrying the other electrode, a conductor rod insulated from the plunger, a pressure-actuated block movable in respect to said plunger and forced into contact with said conductor rod by pressure in the cylinder, and means for positively separating the conductor rod and block after the plunger has separated the electrodes and produced the spark. 100 105

7. The combination of the cylinder carrying one of the electrodes of a make-and-break igniter, a sliding plunger carrying the other electrode, a conductor rod insulated from the plunger, and a pressure-actuated block movable in respect to said plunger and forced into contact with said conductor rod by pressure in the cylinder, said block having hooked legs for engagement with a fixed member of the device to effect positive separation of the conductor rod and block. 110 115 120

8. The combination of the cylinder of an explosive engine, a plug open at its inner end to said cylinder and having at said inner end a bridge bar carrying one of the electrodes of a make-and-break igniter, a plunger guided in said plug and having in its inner end a second plug carrying the other electrode and containing a chamber likewise open to the pressure in the cylinder, said second plug being insulated from the plunger, a 125 130

conductor rod carried by the plunger and insulated from said second plug and a pressure-actuated block contained in the chamber of said second plug and serving to make and break electrical connection between said plug and the conductor rod.

In testimony whereof, I have signed my

name to this specification, in the presence of two subscribing witnesses.

ROBERT H. KOENIG.
